WILLIAM E. YOULE, OF LOS ANGELES, CALIFORNIA.

UNDERREAMER.

Application filed October 2, 1922. Serial No. 591,745.

This invention relates to underreamers for reaming well-holes below the well casing, and is particularly directed to the impact type of underreamers designed for use in connection with the standard cable system of drilling.

The first consideration in producing an efficient underreamer is to provide a tool of extreme simplicity both as to construction and operation, of maximum strength, especially in small sizes, and which is exceedingly positive in its operation and is capable of sustaining severe shocks and strains without overloading any one part of the tool.

One of the major objects of this invention resides in the provision of a new type of underreamer characterized by having one reaming cutter or bit slideable in the body relative to the opposed cutter and in an arcuate path, the opposed cutter being approximately stationary as to longitudinal translation and supported to tilt in a collapsing operation under control of the sliding cutter.

Another object is to provide for a quick immediate release of the cutters when stuck in the well bore, such release being accomplished without disengagement of the dovetails of the cutter shanks from full contact against the outthrust surfaces of the companion dove-tail ways in the body, such full contact maintaining during the "whip" of the tool in a reaming operation.

Another object is to provide an underreamer in which all possibility of losing the cutters in the well-bore is eliminated, the parts being so proportioned and arranged that in case the supporting means of either cutter be broken the other cutter will hold the broken cutter against loss from the body.

A further object is to provide an underreamer having one tilting and one sliding cutter each provided with dove-tail shanks engaging companion dove-tail ways in the body, and in which neither cutter shank has a pivotal action on outthrust surfaces of the ways.

Another object resides in the provision of a spring actuated rod for supporting the sliding cutter, with intermediate connections between the rod and cutter compensating for the arcuate movement of said cutter.

Another object is to provide a spring and

rod container removable laterally from the body as a self-contained unit, and in which the spring may be maintained under tension during removal of said unit.

A further object resides in providing an underreamer in which in-thrusts are transmitted directly from one cutter to the other below the body, and in which the up-thrust bearing surfaces are arranged to relieve the cutter shanks and dove-tails of excessive strains.

Another object resides in the proportioning and arrangement of parts by which it is possible to provide large dove-tails well set into the body, cutter shanks of exceptionally large cross-sectional area, exceptionally large and direct up thrust bearing surfaces, a non-removable support for the tilting cutter which will not prevent a removal of said cutter, cooperation between the two cutters which will positively insure their expansion, exclusion of such dirt or foreign matter as would interfere with free functioning of the parts and cause excessive wear, and to provide a one piece body in which all the recesses are exposed and easily cleaned when the cutters are removed.

A further object resides in the manner of removing the cutters by a manipulation which could not possibly occur in a well-bore.

Various other objects and advantages will be more fully apparent from the following description of the accompanying drawings which form a part of this disclosure, and which illustrate a preferred form of embodiment of the invention.

Of the drawings:

Fig. 1 is an elevation of my improved underreamer, the cutters being in expanded position.

Fig. 2 is a similar elevation of the lower portion of the underreamer, the cutters being in collapsed position.

Fig. 3 is an enlarged bottom plan view of Fig. 1.

Fig. 4 is an enlarged bottom plan view of Fig. 2.

Fig. 5 is a central vertical section showing the cutters in collapsed position.

Fig. 6 is a vertical section on line 6—6 of Fig. 10, showing the cutters in expanded position.

Fig. 7 is a section similar to Fig. 6, show-

ing the cutters in partially collapsed or in release position.

Fig. 8 is a detail elevation illustrating the manner of removing the spring container 5 for disconnection of the spring rod from the sliding cutter.

Fig. 9 is an elevation of the lower position of the underreamer looking at the left-hand side of Fig. 1.

10 Fig. 10 is an elevation looking at the right-hand side of Fig. 1.

Fig. 11 is a central vertical section of the lower portion of the body.

15 Fig. 12 is an enlarged bottom plan view of the body.

Fig. 14 is an enlarged section on line 14—14 of Fig. 5.

20 Fig. 15 is a vertical section on line 15—15 of Fig. 6.

Fig. 16 is an enlarged perspective view of the tilting cutter, and

25 Fig. 17 is an enlarged perspective view of the sliding cutter.

In the drawings, 1 designates the body of the underreamer having the usual tapered pin 2 for attachment to the tool string, and provided at its lower end with opposed 30 open slipways 3 and 4 to receive the shanks of the cutters. The side walls of the respective slip-ways are grooved to provide dove-tail ways 5 and 6, the guideways 5 defining 35 outthrust bearing surfaces 7 which are longitudinally angled upwardly and outwardly (see Fig. 11), and the guide-ways or slip-ways 6 defining out-thrust bearing surfaces 8 which are of arcuate form. An intermediate web 9 provides an abutment or seat 10 which supports the tilting cutter and the upper wall 11 of the slip-way 3 provides an 40 inwardly and upwardly angled up-thrust surface which will be engaged by the upper end of the shank of the tilting cutter as will later be explained. The lower end of the body provides transverse up-thrust bearing 45 faces or surfaces 12 and 13 on each side of the respective slip-ways, these up-thrust surfaces being preferably angled or inclined 50 inwardly and upwardly towards each other. These faces 12 and 13 preferably constitute the extreme lower end faces of the body. The side wall of the body above the slip-way 4 is longitudinally grooved to provide a 55 spring chamber 15 which communicates with said slip-way, the side walls of said chamber being in plane with the base of the dove-tail ways 6 so as to afford an easy machining of said ways and said chamber.

60 The spring chamber 15 is adapted to receive a self-contained spring rod unit comprising a cover plate or spring container 16 having an inwardly extending lateral lug provided with a vertical bore 18 through 65 which a spring rod 19 extends, and a spring

20 which surrounds said rod between the lug 17 and a square nut 21 screwthreaded on the upper end of the rod (see Figs. 5 and 14). The lower end of the plate 16 is provided with downwardly projecting angled lips 22 which engage behind angled abutment surfaces 23 on the body to hold the lower end of the spring carrier in place and the free end of the lateral lug 17 engages into a recess 24 in the body, so that the strains occasioned by the tension of the spring will be transmitted directly to the body. The upper wall of the chamber 15 is angled inwardly and downwardly and has a central groove 25, and the upper end of the plate 16 is correspondingly angled and is provided with a lug 26 adapted to mesh into the groove 25 when the plate is in place. The plate 16 is secured in place by a bolt 27 which extends laterally through aligned apertures in the body and in the lug 26, with the bolt retained in place by a split cotter pin 28, (see Fig. 10). To facilitate a removal of the plate after the bolt has been retracted, a recess 29 is provided at the upper end of the lug 26 into which may be inserted a suitable tool to pry the plate loose.

The above described organization of parts provides a one piece body having no centrally bored spring chamber and which therefore does not require any screw-threaded joints or sub-connections.

Describing the reaming cutters or bits, attention is directed to the several views, and particularly to Figs. 16 and 17. The tilting cutter 30 has an upwardly extending shank 31, the upper end of which is angled to the same degree as is the upper wall of the slip-way 3, and is provided with an inwardly extending pintle nose or pivot projection 32 which has a sliding pivotal engagement upon the abutment or seat 10 on the web 9 of the body. On opposite sides of the shank 31, the body of the cutter 30 extends laterally to form up-thrust bearing surfaces 33 angled for cooperative engagement with the transverse up-thrust bearing surfaces 12 of the body when the cutters are in expanded position. Dove-tail ribs 34 extend outwardly from the side walls 11 of the shank 31 and when the cutter is in position in the slip-way 3, these dove-tails slidably engage in the dove-tail ways 5, their outer edges 35 providing outthrust bearing surfaces for engagement with the out-thrust bearing surfaces 7 formed by said ways.

The sliding reaming cutter or bit 36 has an upwardly extending shank 37 having its upper end bifurcated to receive the lower end of a link 38 to which it is pivotally connected by a pin 39, the upper end of said link extending between the arms of a forked head 40 on the lower end of the spring rod 19, and pivotally connected thereto by a pin 130

41. On opposite sides of the shank 37, the body of the cutter 36 extends laterally to form up-thrust bearing surfaces 42 angled for cooperative engagement with the transverse up-thrust bearing surfaces 13 of the body when the cutters are in expanded position. Dove-tail ribs 43, extend outwardly from the side wall of the shank 37 and when the cutter is in position in the slip-way 4, 10 these dove-tails slidably engage in the dove-tail ways 6, their outer edges 44 providing arcuate out-thrust bearing surfaces which are longitudinally curved correspondingly to the arcuate out-thrust bearing surfaces 8 15 formed by the companion dove-tail ways 6.

The opposed transverse surfaces of the bodies of the two cutters are formed to intermesh when the cutters are in collapsed position, as shown in Fig. 5. When the cutters are in such collapsed position a latch shoulder 45 on the cutter 36 engages beneath a companion latch shoulder 46 on the cutter 30, and as these shoulders are approximately horizontal when the cutters are 25 collapsed, the cutters will remain collapsed until the reamer is jarred, whereupon the tilting cutter 30 will swing away from the sliding cutter 36 under the influence of 30 gravity and permit an upward movement of the sliding cutter under the influence of the spring to expand the cutters.

Upon such release of the cutters and during the upward travel of the sliding cutter, the corner 47 of the cutter 36 will ride upwardly on the transverse expanding surface 48 of the cutter 30 to initially expand the cutters, and then the surface or abutment shoulder 49 of the cutter 36 will engage the surface or abutment shoulder 50 of the cutter 30 and complete the expanding of the cutters.

The surface 49 is of the same curvature as are the arcuate dove-tails 43 and the surface 50 of the cutter 30 is correspondingly curved 15 so that during any downward movement of the sliding cutter 36 from its expanded position and while the surfaces 49 and 50 are in engagement, the dove-tails of both cutters will remain in engagement with the out-thrust bearing surfaces 7 and 8 of the respective dove-tail ways.

When the cutters are in expanded position, as shown in Fig. 6, the surfaces 49 and 50 further serve as in-thrust bearing surfaces, their cooperative engagement transmitting in-thrusts directly from one cutter to the other below the body, thereby relieving the cutter shanks and their dove-tails of a large portion of the strains caused by 10 such in-thrusts, which are usually due to glancing blows of the cutters against the walls of the well bore.

In instances where the cutters become stuck in a well bore it becomes necessary to 15 partly collapse the cutters so as to release

the cutters. This is accomplished by pulling upwardly on the body of the underreamer, causing a longitudinal sliding movement of the arcuate surfaces 49 and 50 relative to each other and an initial collapsing 70 of the two cutters. By reason of the curvature of the arcuate dove-tails 43 of the sliding cutter this initial collapsing or release of the cutters is accomplished without withdrawing the dove-tails of the respective cutters away from their full contact with the out-thrust bearing surfaces of the dove-tail ways, therefore, I provide for a quick release of the cutters without any slapping 75 of the dove-tails in their respective ways. 80 This is an important consideration as in many types of underreamers such slapping of the cutters in their slip ways during a release of the cutters and during the "whip" 85 of the drill cable, constitutes one of the major causes for crystallization of the cutter shanks and the ripping out of the dove-tails from the body.

As it is desirable to provide a positive tilting of the cutter 30 to collapsed position, the upper end of the sliding cutter shank is provided with a cam shoulder 51 which during the downward movement of the sliding cutter, is adapted to engage the end of the nose 32 of the tilting cutter, (see Fig. 7) 90 and positively swing said cutter to the collapsed position shown in Fig. 5.

The underreamer of the present invention is also constructed so as to prevent loss of the cutters in the well bore and contributing to this object, the cutters are provided with shoulders 52 and 53 which may be considered abutment shoulders; they are adapted to interlock when the cutters are in collapsed position.

In considering the possibility of breakage of parts, it will be quite evident that the cross-sectional area of the supporting nose 32 of the tilting cutter is of such dimensions that breakage thereof is a remote possibility. However, if this nose 32 should become broken off, the cutter 30 will not drop from the body when in expanded position, by reason of the fact that the longitudinally angled dove-tails and dove-tail ways of 110 said cutter together with the arcuate surfaces 49-50 form, in effect, a wedge preventing a dropping of the cutter 30 so long as even a relatively short portion of the dove-tails 34 remain in the companion ways 5, and when the cutters are in collapsed position the engagement of the latch shoulder 46 on the latch shoulder 45 will hold the cutter 30 from dropping. It is therefore 115 evident that even though a major portion of the shank 31 should be broken off, the cutter 30 will be retained as will the broken off portion of said shank.

As to the cutter 36 it will be plain that the weakest portion of the shank 37 is at 120

its pivotal connection with the link 38, and outwardly from the body to a position that the shank will not break below the safety shoulder 53. As soon as the cutter 30 to disconnect the spring rod unit from the 36 slides through its initial release, to the tool. The tool is then suspended, allowing 70 position shown in Figure 7, gravity will cause the cutter 30 to tilt inwards and bring the cam shoulder 51 below the nose 32, the safety shoulder 52 below the shoulder 51, whereupon, by manually spreading apart 53 of the sliding cutter and prevent same the two cutters to a maximum degree the from dropping from the body. The sliding cutter may first be withdrawn from 75

10 In the event that either of the pins 39 or 41 should shear off, or in case the head 40 or spring rod 19 become broken, or further, in case the nut 21 should strip off the rod 19, no parts will be lost in the well bore, as body and be also removed. 75

15 in either of these cases the cutters will function normally to bring them to an interlocking collapsed position with the weight of both cutters sustained by the nose 32 of the cutter 30 resting upon the seat 10 of the body web 9. 80

20 With the cutters in collapsed position for faces of the body and cutters relieve the cutters having exceptionally broad bearing surfaces, and in which the

25 surface of a shoulder 54 on the cutter shank 31 and the outer and the arcuate dove-tail of the one cutter 37 are approximately parallel with the dove-tails, maintain their full normal contact with the out-thrust bearing surfaces of the casing wall. When these surfaces are below the casing shoe at the lower end of the dove-tail ways, thereby preventing a 90 casing, a slight jarring on the tool string looseness and slapping of the dove-tails in will suffice to cause an automatic expansion of the ways, which ordinarily produce excess 30 of the cutters. If desired the usual split retaining ring may be employed to hold the cutters collapsed while lowering the tool into the casing. 95

35 With the cutters held in their working position by the spring 20, as shown in Figures 1 and 6, and the underreamer is drawn upwardly into the well casing, the casing shoe 55 first contacts the well-bore. The other cutter remains slanting shoulder 54 of the sliding cutter, stationary during reaming, so during the operation of the reamer we have one station- 105 drawing down the sliding cutter and spring 20, and forcing the cutter 36 to slide on the stationary cutter, and one sliding cutter which is 40 ways 6 and on the face 50 until it assumes the position shown in Fig. 7 with its corner surfaces of its slide ways, this arrangement 45 preventing dirt entering under the dove-tail 30. Upon a further upward movement of the underreamer into the well casing, the shoe will also come in contact with the outer surface 47 below the face or surface 50 of the cutter 30, preventing the cutter 30 inwardly, so that both cutters 50 will then be brought together in inter-mesh- 110 reaming operation and when the cutters are 115

50 collapsed position. (See Fig. 5). to be fully collapsed, and as the tilting cutter pivots on the body web 9 there is no cutter pivots on the body web 9 there is no pivotal action of said cutter on its dove-tails. Therefore I have eliminated all pivot action 120 following manner. With the cutters in expanded position and resting upon any flat surface, a wedge member 56 is inserted into an aperture 57 in the plate 16 between the ways. 125

60 lug 17 and the head 40 so as to slightly force the spring rod 19 downwards and take the one wearing dove-tail, one bolt connection 130 the spring rod 19 off the pins 39 and 41, the pin apertures in the link 38 being, and a corresponding increase in strength for this purpose slightly larger than said pins. The cotter pin 28 and bolt 27 are relatively lighter spring may be used than in then removed and the spring rod unit swung the ordinary types of underreamers, and the 135

provision of a self contained spring rod unit removable laterally, permits a one piece body in which the spring chamber is aligned with one of the open slip-ways and can be 5 easily machined.

In a four and one-half inch underreamer the arcuate dove-tails permit a transverse release of three-eighths of an inch with a down pull of only three quarters of an inch. 10 This small movement of the sliding cutter during reaming means less wear, less shock, less crystallization and less strain on the bolt and spring.

Furthermore this movement is so slight 15 that nothing large enough to do damage can get between the up-thrust bearing surfaces. At all times during reaming, the sliding cutter of a four and one-half inch underreamer has a full bearing over four inches 20 in length on its dove-tails.

The tilting cutter is held in the body by its heavy lug or nose which engages the web between the slip-ways. The lug extends across the entire face of the cutter shank and 25 locks into the body without the use of keys or pins. Even should the lug shear, this cutter cannot drop from the body as long as the other cutter is present. The cooperating arcuate inthrust bearing surfaces of the 30 cutters extend the full width of the cutters and insure an even action against a glancing blow on either cutter.

The collapsing action of the cutters is made positive by the cam shoulder on the 35 sliding cutter engaging the supporting nose of the tilting cutter, and this positive action also insures the cooperation of the two safety interlocking shoulders on the cutters.

From an inspection of the drawings, the 40 simplicity and strength of the body construction will be apparent, a continuous slot serving for both the sliding cutter and the spring, and the side walls of the spring chamber are solidly braced against crushing, 45 by the spring container. With the operating parts removed all the slipways and recesses in the body are exposed and are easily cleanable. This method of mounting the spring and spring rod makes possible the 50 elimination of a drilled spring chamber in the body, and obviates the necessity of a jointed body.

The body and cutters have been so designed as to reduce wear to a minimum and 55 the movement of the sliding cutter in reaming is so small that its wearing effect will be negligible. The tilting cutter, which in reaming does not move in the body, can wear at only one point, the broad arcuate in-thrust bearing surface below the body. Wear at this point can easily be compensated for by building up this arcuate bearing surface.

Furthermore as the arcuate surfaces and 60 dove-tails wear evenly, these may be built

up, and refinished to take up for wear, without any work on the body.

While the specific form of construction herein illustrated and described provides a tool fully capable of fulfilling all of the objects primarily stated, it is to be understood that I do not wish to limit the invention to the one form of embodiment disclosed, for it is susceptible of embodiment in various other forms, all coming within the scope of 75 the following claims.

I claim:

1. An underreamer having an up-thrust bearing surface constituting the extreme lower end face of the body, and having an 80 arcuate dovetailed open guideway for guiding a cutter to slide in an arc, and extending upwardly from said bearing surface.

2. An underreamer body having an up-thrust bearing surface constituting the 85 extreme lower end face of the body and having a longitudinally disposed arcuate slipway uniformly curved upwardly and outwardly from the said upthrust bearing surface, the uniform curvature enabling the 90 same to guide a cutter to slide in an arc.

3. An underreamer body having an up-thrust bearing surface constituting the extreme lower end face of the body and having 95 a dovetailed guideway capable of guiding a cutter to slide in an arc longitudinally disposed in the body and extending upwardly from the said up-thrust bearing surface and having arcuate out-thrust bearing surfaces uniformly curved upwardly and 100 outwardly.

4. An underreamer body having an up-thrust bearing surface constituting the extreme lower end face of the body and having 105 a dovetail guideway for guiding a cutter to slide in an arc longitudinally disposed and extending upwardly from said up-thrust bearing surface, said guideway having arcuate out-thrust bearing surfaces of uniform curvature bowed outwardly at their 110 middle portions.

5. An underreamer body having an up-thrust bearing surface constituting the extreme lower end face of the body and having 115 two opposed longitudinally disposed guideways extending upwardly from said bearing surface, one of said guideways having straight out-thrust bearing surfaces and the other having arcuate out-thrust bearing surfaces of uniform curvature capable of 120 guiding a cutter to slide in an arc.

6. An underreamer body having an up-thrust bearing surface on its lower end, and two opposed longitudinally disposed open slip-ways extending upwardly from its lower 125 surface, and an intermediate web having means to cooperate with one of the cutters to support the same, one slip-way defining straight out-thrust bearing surfaces and the other defining uniformly curved arcuate 130

out-thrust bearing surfaces, and constituting a guideway for guiding a cutter to slide in an arc.

7. An underreamer body having an up-thrust bearing surface on its lower end, and two opposed longitudinally disposed open slip-ways extending upwardly from its lower surface, one slip-way defining straight out-thrust bearing surfaces longitudinally angled upwardly and outwardly and the other slip-way defining longitudinally disposed arcuate out-thrust bearing surfaces of uniform curvature, constituting a guideway for guiding a cutter to slide in an arc.

8. In an underreamer, the combination of a body having a groove in its side wall extending upwardly from its lower surface, the lower portion of said groove forming an open slip way and the upper portion thereof of forming a spring chamber, a spring located in the spring chamber, the walls of the lower portion of the groove being formed to provide arcuate out-thrust bearing surfaces, a cutter guided in the slipway and cooperating with the spring, and a removable cover for the spring chamber.

9. An underreamer body having two opposed open slipways extending upwardly from its extreme lower end face with said face on opposite sides of the slip-ways providing opposite up-thrust bearing surfaces angled upwardly and inwardly towards each other, one slip-way having its top wall angled inwardly and upwardly and its side walls undercut to provide dove-tail ways defining out-thrust bearing surfaces, and the other slip-way being undercut to provide dove-tail ways defining arcuate out-thrust bearing surfaces of uniform curvature, constituting guideways to guide a cutter in an arc.

10. In an underreamer, the combination of a body, a cutter having a body-portion and a shank extending upwardly therefrom having means for supporting the cutter, said shank provided with longitudinally disposed, arcuate dovetail ribs extending from its opposite side walls, the said underreamer body having arcuate guideways receiving the dovetail ribs and guiding the cutter, and means for controlling the cutter to move the same up or down in the guideways.

11. In an underreamer, the combination of an underreamer body, a cutter having a body-portion and a shank extending upwardly therefrom having means for supporting the cutter, said shank having up-thrust bearing surfaces on either side of the shank, said shank also having dovetailed ribs with faces constituting out-thrust bearing faces, the body of the cutter below the shank having an arcuate expanding surface on its inner face, said underreamer body having arcuate guideways for receiving said ribs, and means cooperating with the cutter to

move the same up and down in the underreamer body.

12. In an underreamer, the combination of an underreamer body, a cutter having a body-portion provided with an arcuate expanding surface on its inner face and provided with a shank having means for supporting the cutter extending upwardly from said body portion and having longitudinally disposed, arcuate, dovetail ribs extending from its side faces, said underreamer body having arcuate guideways receiving the dovetail ribs, and means cooperating with the cutter to move the same up or down in the guideways.

13. In an underreamer, the combination of an underreamer body, a cutter having a body-portion provided with a latching shoulder and with an arcuate expanding surface on its inner side, said cutter having a dovetail shank extending upwardly from the body portion, and having an abutment shoulder on the body portion, and a companion cutter having an abutment shoulder to cooperate with the latching shoulder when the cutters are in a collapsed position, and to engage the first named abutment shoulder and cooperate with the same to hold the cutters in an expanded relation.

14. An underreamer having a body, a reaming cutter tiltingly supported in the lower end of the body, and a longitudinally movable reaming cutter mounted and positively guided in the body in an arcuate path, the two cutters having a cooperative cutter expanding engagement.

15. An underreamer having a body, a spring actuated rod slidable in the body, a longitudinally movable reaming cutter connected with said rod and mounted and positively guided in the body in an arcuate path, and a second reaming cutter tiltingly supported in the body independently of said rod and cooperating with the slidable cutter in a cutter expanding operation.

16. An underreamer having a body, a spring actuated rod slidable in the body, a longitudinally movable reaming cutter connected with said rod and slidable in the body in an arcuate path, and a second reaming cutter tiltingly supported in the body independently of said rod, said cutters having inner surfaces cooperating to cause the cutters to expand when in one position, and to permit said cutters to collapse when in another position, and other cooperating surfaces whereby a collapsing movement of the sliding cutter effects a positive collapsing movement of the tilting cutter.

17. An underreamer having a body, a longitudinally immovable cutter pivoted in the body to tilt transversely, a second cutter longitudinally slidable in the body and positively guided in an arcuate path, and automatic means adapted to translate said sec-

ond cutter, said cutters being free of each other and normally held expanded by said means operating the second cutter.

18. An underreamer having a body, a cutter pivoted in the body to tilt transversely, a second cutter longitudinally slideable in the body and positively guided in an arcuate path, and automatic means connected to said second cutter and functioning to elevate said second cutter, the cutters being free of each other and expanding upon the upward movement of said second cutter.

19. An underreamer having a body, a longitudinally immovable cutter pivotally supported on the body to tilt transversely, and a second cutter free from the first cutter and spring-actuatedly mounted in the body to move longitudinally with respect to said body and first cutter and positively guided in an arcuate path, said cutters expanding during an upward movement of said second cutter.

20. An underreamer having a body, a longitudinally immovable cutter supported in the body to tilt transversely and projecting from the lower end thereof, and a second cutter having means for positively guiding the same to slide in the body in an arcuate path and projecting from the lower end thereof, the abutting surfaces of the two cutters cooperating to expand the cutters during an upward movement of the second cutter and to permit a collapsing of the cutters during a downward movement of the second cutter and to interlock the two cutters.

21. An underreamer having a body, a cutter tiltingly supported in the body, a second cutter longitudinally slideable in the lower end of the body in an arcuate path and in respect to the first cutter, and means for automatically elevating the second cutter causing said cutters to expand, said cutters having cooperating inthrust bearing surfaces abutting against each other below the body when the cutters are in expanded position.

22. An underreamer having a body provided with open slip-ways to receive reaming cutters, a cutter in one slip-way supported to tilt transversely, a second cutter longitudinally slideable in the other slip-way in respect to the first cutter and in an arcuate path, and automatic means for elevating the second cutter to expand both cutters, the cutters having body portions and shank portions, said body portions with co-operating inthrust bearing surface extending laterally beyond the shanks.

23. An underreamer having a body, a cutter tiltingly supported by the body, a second cutter longitudinally slideable in the body downwardly with an arcuate path and in respect to the first cutter, and means for automatically elevating the second cutter to ex-

pand the cutters, said cutters having cooperating arcuate inthrust bearing surfaces abutting against each other when the cutters are in expanded position.

24. An underreamer having a body provided with open slip-ways to receive reaming cutters, a cutter in one slip-way supported to tilt transversely, a second cutter longitudinally slideable in the other slip-way in an arcuate path and in respect to the first cutter, and automatic means for elevating the second cutter to expand both cutters, the cutters having cooperating arcuate inthrust bearing surfaces abutting against each other when the cutters are in expanded position, and with the arcuate inthrust bearing surfaces being of a curvature corresponding to the arcuate path of movement of the second cutter.

25. An underreamer having a body, a longitudinally-immovable cutter supported in the body to tilt transversely and projecting below the lower end of the body, a second cutter projecting below the lower end of the body and positively guided to slide longitudinally in the body in an arcuate path and in respect to the first cutter, and means for automatically elevating the second cutter to expand both cutters, the cutters being provided with up-thrust bearing surfaces for abutment with the lower end of the body when said cutters are expanded.

26. An underreamer having a body provided with open slip-ways to receive reaming cutters and having up-thrust bearing surfaces on opposite sides of the slip-ways, a longitudinally-immovable cutter in one slip-way supported to tilt transversely, a second cutter longitudinally slideable in the other slip-way with means for positively guiding the same to move in an arcuate path, and means for elevating said second cutter to cause the cutters to expand, said cutters having up-thrust bearing surfaces for contacting said up-thrust bearing surfaces of the body when the cutters are expanded.

27. An underreamer having a body provided with open slip-ways to receive reaming cutters and having its under surface on opposite sides of the slip-ways formed to provide opposite up-thrust bearing surfaces angled inwardly and upwardly, a longitudinally-immovable cutter in one slip-way supported to tilt transversely, a second cutter longitudinally slideable in the other slip-way with means for positively guiding the same to move in an arcuate path, and means for elevating said second cutter to cause the cutters to expand, the cutters having shanks extending upwardly into the slip-ways and provided with inwardly and upwardly angled up-thrust bearing surfaces for cooperation with the up-thrust bearing surfaces of the body when in expanded position.

28. An underreamer having a body pro-

- viding a first slip-way defining straight out-thrust bearing surfaces and an opposed slip-way defining arcuate out-thrust bearing surfaces, a longitudinally immovable tilting cutter in the first slip-way, a longitudinally slideable cutter in the opposed slip-way, the cutters having out-thrust bearing surfaces for engaging the out-thrust bearing surfaces of their respective slip-ways and inner surfaces 10 cooperating to expand the cutters upon an elevation of the slideable cutter, the upper portions of said inner surfaces having an arcuate curvature corresponding to that of the arcuate out-thrust bearing surfaces of 15 the slideable cutter, whereby upon an initial downward movement of the sliding cutter an initial collapsing of the cutters is effected while maintaining a full engagement of the cooperating out-thrust bearing surfaces.
- 20 29. An underreamer including a body having a side opening spring chamber, a cutter longitudinally slideable in the body below said chamber, a closure for said chamber, a rod and actuating spring carried by said closure, and means connecting the rod with said cutter.
- 30 30. An underreamer including a body having a side opening spring chamber a cutter longitudinally slideable in the body below 30 said chamber, a closure for said chamber, a spring actuated rod carried by said closure, a spring exerting an upward pull on the rod, means connecting the rod with said cutter, and independent means for relieving said 35 connecting means of the tension of the spring for a disconnection of said connecting means to permit a removal of the closure, spring rod and spring as a unit.
- 31 31. An underreamer including a body having opposed open slip-ways to receive reaming cutters, and an intermediate web, a cutter in one slip-way and having a projection engaging said web for tiltingly supporting said cutter, said projection extending into 40 the opposed slip-way, a second cutter longitudinally slideable in the opposed slip-way and having a cam shoulder adapted upon downward movement of the sliding cutter, to engage the projection on the tilting cutter, 45 and positively move it to collapsed position.
- 50 32. An underreamer including a body having a straight slip-way and an opposed arcuate slip-way, each extending upwardly from the lower surface of the body, a cutter having a straight shank extending into the straight slip-way and supported on the body to tilt transversely, a second cutter having an arcuate shank longitudinally slideable in the arcuate slip-way, and automatic means 55 for translating the second cutter to cause an expanding co-engagement of both cutters.
- 60 33. An underreamer including a body having a straight slip-way and an opposed arcuate slip-way, each extending upwardly from the lower surface of the body and defining out-thrust bearing surfaces, a cutter having a straight shank extending into the straight slip-way and supported on the body to tilt transversely, a second cutter having an arcuate shank longitudinally slideable in the arcuate slip-way, and automatic means for translating the second cutter, the inner walls of the cutters having co-engaging latch shoulders and expanding surfaces causing a three step expansion of the cutters, the surfaces effecting the final expanding step being of arcuate form corresponding in curvature to the arcuate slip-way, whereby an initial collapsing of the cutters may be effected with the cutter shanks maintained in full contact with the out-thrust bearing surfaces of the body.
- 65 34. An underreamer including a body having opposed open slip-ways extending upwardly from its lower surface, one of said slip-ways being straight and having undercut side-walls defining straight dove-tail ways and the other of said slip-ways having undercut sidewalls defining arcuate dove-tail ways, a cutter having a shank in the straight slip-way, provided with straight dove-tail ribs engaging within the straight dove-tail ways and supported on the body to tilt transversely, a second cutter having a shank longitudinally slideable in said other slip-way and provided with arcuate dove-tail ribs engaging within the arcuate dove-tail ways, and automatic means for actuating the second cutter to cause an expansion of both cutters.
- 70 35. An underreamer including a body having opposed open slip-ways extending upwardly from its lower surface, said lower surface on opposite sides of the slip-ways defining opposed up-thrust bearing surfaces angled upwardly and inwardly towards each other, one of said slip ways having undercut side-walls defining straight dove-tail ways angled upwardly and outwardly and the other of said slip-ways having undercut side walls defining arcuate dove-tail ways, a cutter having a shank in said one slip-way provided with straight dove-tail ribs engaging within the straight dove-tail ways and supported on the body to tilt 75 transversely, a second cutter having a shank longitudinally slideable in said other slip-way and provided with arcuate dove-tail ribs engaging within the arcuate dove-tail ways, and automatic means for actuating the second cutter to cause an expansion of both cutters.
- 80 36. An underreamer including a body having opposed open slip-ways extending upwardly from its lower surface, said lower surface on opposite sides of the slip-ways defining opposed up-thrust bearing surfaces angled upwardly and inwardly towards each other, one of said slip ways having undercut side-walls defining straight dove-tail ways angled upwardly and outwardly and the other of said slip-ways having undercut side walls defining arcuate dove-tail ways, a cutter having a shank in said one slip-way provided with straight dove-tail ribs engaging within the straight dove-tail ways and supported on the body to tilt 85 transversely, a second cutter having a shank longitudinally slideable in said other slip-way and provided with arcuate dove-tail ribs engaging within the arcuate dove-tail ways, and automatic means for actuating the second cutter to cause an expansion of both cutters.
- 90 37. An underreamer including a body having opposed open slip-ways extending upwardly from its lower surface, said lower surface on opposite sides of the slip-ways defining opposed up-thrust bearing surfaces angled upwardly and inwardly towards each other, one of said slip ways having undercut side-walls defining straight dove-tail ways angled upwardly and outwardly and the other of said slip-ways having undercut side walls defining arcuate dove-tail ways, a cutter having a shank in said one slip-way provided with straight dove-tail ribs engaging within the straight dove-tail ways and supported on the body to tilt 95 transversely, a second cutter having a shank longitudinally slideable in said other slip-way and provided with arcuate dove-tail ribs engaging within the arcuate dove-tail ways, and automatic means for actuating the second cutter to cause an expansion of both cutters.
- 100 38. An underreamer including a body having opposed open slip-ways extending upwardly from its lower surface, said lower surface on opposite sides of the slip-ways defining opposed up-thrust bearing surfaces angled upwardly and inwardly towards each other, one of said slip ways having undercut side-walls defining straight dove-tail ways angled upwardly and outwardly and the other of said slip-ways having undercut side walls defining arcuate dove-tail ways, a cutter having a shank in said one slip-way provided with straight dove-tail ribs engaging within the straight dove-tail ways and supported on the body to tilt 105 transversely, a second cutter having a shank longitudinally slideable in said other slip-way and provided with arcuate dove-tail ribs engaging within the arcuate dove-tail ways, and automatic means for actuating the second cutter to cause an expansion of both cutters.
- 110 39. An underreamer including a body having opposed open slip-ways extending upwardly from its lower surface, said lower surface on opposite sides of the slip-ways defining opposed up-thrust bearing surfaces angled upwardly and inwardly towards each other, one of said slip ways having undercut side-walls defining straight dove-tail ways angled upwardly and outwardly and the other of said slip-ways having undercut side walls defining arcuate dove-tail ways, a cutter having a shank in said one slip-way provided with straight dove-tail ribs engaging within the straight dove-tail ways and supported on the body to tilt 115 transversely, a second cutter having a shank longitudinally slideable in said other slip-way and provided with arcuate dove-tail ribs engaging within the arcuate dove-tail ways, and automatic means for actuating the second cutter to cause an expansion of both cutters.
- 120 40. An underreamer including a body having opposed open slip-ways extending upwardly from its lower surface, said lower surface on opposite sides of the slip-ways defining opposed up-thrust bearing surfaces angled upwardly and inwardly towards each other, one of said slip ways having undercut side-walls defining straight dove-tail ways angled upwardly and outwardly and the other of said slip-ways having undercut side walls defining arcuate dove-tail ways, a cutter having a shank in said one slip-way provided with straight dove-tail ribs engaging within the straight dove-tail ways and supported on the body to tilt 125 transversely, a second cutter having a shank longitudinally slideable in said other slip-way and provided with arcuate dove-tail ribs engaging within the arcuate dove-tail ways, and automatic means for actuating the second cutter to cause an expansion of both cutters.

36. An underreamer body having two opposed longitudinally disposed slip-ways extending upwardly from its lower surface, one slip-way defining straight out-thrust bearing surfaces and the other defining arcuate out-thrust bearing surfaces of uniform curvature, a cutter in one slip-way, and a cutter in the other slip-way, said cutters having faces which abut against each other and co-operate to hold the cutters expanded.

37. An underreamer body having two opposed longitudinally disposed open slip-ways extending upwardly from its lower surface and an intermediate cutter-supporting web, one slip-way defining straight out-thrust bearing surfaces and the other defining uniformly curved arcuate out-thrust bearing surfaces, a cutter guided to slide on the said arcuate bearing surfaces and a cutter co-operating with the same and mounted in the other slipway.

38. In an underreamer the combination of a body, a cutter mounted on one side of said body with means for holding the same against longitudinal movement in the body, a second cutter mounted on the other side of said body, said second cutter having means for positively guiding the same in

an arc extending downwardly in the body 30 and operating to permit the second cutter to move downwardly with respect to the other cutter and inwardly toward the axis of the body, while the first named cutter is maintained against longitudinal movement 35 in the body.

39. In an underreamer the combination of a body having a straight dove-tailed slip-way providing out-thrust bearing surfaces, and having an arcuate dove-tailed slip-way 40 on its opposite side providing out-thrust bearing surfaces, a cutter in each of said slipways and co-operating so as to have transverse collapsible movement, and capable of an expanding movement with both 45 said cutters in engagement with their out-thrust bearing surfaces.

40. An underreamer including a body having a side opening spring chamber, a cutter longitudinally slidable in the body 50 below said chamber, a closure for said chamber, a spring actuated rod carried by said closure, and means including a pivot connection connecting the rod with said cutter. 55

Signed at Los Angeles, California, this 23d day of September 1922.
